HIS ATTY.

UNITED STATES PATENT OFFICE.

EGBERT ALEXANDER, OF BURLINGAME, CALIFORNIA.

REFILLABLE CARTRIDGE-FUSE.

1,101,897.

Specification of Letters Patent. Patented June 30, 1914.

Application filed September 11, 1913. Serial No. 799,180.

To all whom it may concern:

Be it known that I, EGBERT ALEXANDER, a citizen of the United States, and a resident of the city of Burlingame, county of San Mateo, State of California, have invented 5 a new and useful Improvement in Refillable Cartridge-Fuses, of which the following is a specification.

My invention relates to improved cartridge fuses wherein a cylinder of suitable insulating material is provided with metallic ends to which metallic disks are eccentrically and pivotally secured so that when the said disks are turned upon their pivots the 15 ends of the cylinder are readily accessible for the purpose of inserting a new fuse wire and refilling the interior of the said cylinder with bismuth or a like substance, and the object of my invention is to provide a 20 cheap and practical cartridge fuse that may be readily and easily refilled.

I accomplish these features by means of the device illustrated in the drawings forming a part of the present specification where- 25 in like numerals of reference designate similar parts throughout the said specification and drawings, and in which—

Figure 1 is a broken vertical sectional view of the cartridge disclosing the ends 30 closed and the manner in which the disks are eccentrically secured. Fig. 2 is an end view of Fig. 1. Fig. 3 is a view similar to Fig. 1, but disclosing the eccentrically secured disk in a position that will provide 35 ready access to the interior of the cartridge, and Fig. 4 is an end view of Fig. 3.

Non-arcing cartridge fuses of this type are expensive and when the fuse wire is 40 burnt the same may be replaced and the cartridge restored to its former state of efficiency and usefulness at a small cost by inserting a new fuse therein. I propose to provide the following, a cartridge that may be easily and readily refitted with a new fuse 45 and refilled with the bismuth in the following manner. A cylinder 1, of any suitable insulating material, is provided with the metallic ends 2 having inwardly extending lugs 2' integral therewith. The lugs 2' are 50 perforated and provided with the screws 4 to which is attached the central fuse wire 5. Disks 6 are seated within the ends 2 and are eccentrically secured thereto by means of the screws 4. When the ends of the cylin-

der 1 are closed by the disk 6, as illustrated 55 in Fig. 1 of the drawings, the bismuth therein, which surrounds the fuse wire 5, is retained therein. When it is desired to renew the fuse wire 5, one of the screws 4 is 60 screwed to a position where the disk 6 is free to swing clear of the end 2 as illustrated in Figs. 3 and 4 of the drawings. The interior of the cylinder is then accessible 65 and the old fuse may be removed and a new one inserted without removing the disk 6 from the cartridge. After the new fuse has 70 been inserted the cylinder 1 is refilled with bismuth and the disks 6 are returned within the ends 2 as illustrated in Figs. 1 and 2 of the drawings. The refilled cartridge is 75 now ready for use.

In cartridges of small diameter it is rather difficult to remove the ends without dropping or losing the screws or ends of the said cartridge. For this reason I have 75 provided a refillable cartridge wherein access may be had to the interior of the said cartridge without entirely removing the ends therefrom. The disks 6 are set within the ends 2 so that the screws 4 will not project beyond the ends of the cartridge and interfere with the insertion of the said cartridge into the electric terminals adapted to receive it. 80

It is obvious from the foregoing that I 85 have provided a refillable cartridge fuse that may be easily refilled and restored to a condition for use in a cheap and easy manner.

The details of construction are so suspec- 90 tible of variation that I do not wish to confine myself to the precise construction shown herein but rather to avail myself of any modification that may properly fall within the scope of my invention.

Having thus described my invention what I claim as new and desire to secure by Letters Patent is—

1. A refillable cartridge fuse comprising a 95 cylinder of suitable insulating material; metallic tubular ends having lugs secured to each end of the cylinder; and a disk eccentrically secured to each lug and adapted to close the end of the cylinder.

2. A refillable cartridge fuse comprising a 100 cylinder of suitable insulating material; a metallic tubular end secured to each end of the cylinder and having an inwardly ex-

tending lug; and a disk eccentrically secured within each tubular end and to the inwardly extending lug.

3. A refillable cartridge fuse comprising a cylinder of suitable insulating material; a metallic tubular end secured to each end of the cylinder and having inwardly extending lugs integral with the said tubular ends; a screw secured within each lug; and a disk 10 having an aperture eccentric thereto and

adapted to be engaged by the screw in the lug and to be retained within the end of each tubular metallic end.

In witness whereof I hereunto set my sig-
nature in the presence of two subscribing 15
witnesses.

EGBERT ALEXANDER.
